UNITED STATES PATENT OFFICE.

LOUIS H. HAYS AND ARTHUR R. CURTIS, OF CLEVELAND, OHIO.

CARD-PRINTING ATTACHMENT FOR MARKING-MACHINES.

1,295,745.

Specification of Letters Patent.

Patented Feb. 25, 1919.

Application filed May 11, 1916. Serial No. 96,876.

To all whom it may concern:

Be it known that we, LOUIS H. HAYS and ARTHUR R. CURTIS, citizens of the United States, and residents of Cleveland, in the 5 county of Cuyahoga and State of Ohio, have invented a certain new and useful Card-Printing Attachment for Marking-Machines, of which the following is a specification.

10 In the art of laundry marking machines, it has been customary to provide type wheels so arranged that the wheels may be turned to present the selected type thereon to printing position, and then to move the type 15 wheels downwardly and forwardly to engage the articles to be printed on between the type wheels and a stationary platen.

The objects of our invention are to provide a device in the nature of an attachment 20 of simple, durable and inexpensive construction, that may readily, quickly and easily be applied to a laundry marking machine for the purpose of retaining a large number of cards, tags or the like, and for utilizing 25 the movement of the type wheels for the purpose of removing these cards or tags one at a time from the magazine or container and placing them over the stationary platen and there holding them stationary while the 30 type wheels complete the last part of their operative movement and make an impression upon the card.

A further object is to provide means whereby the movement of the type wheels 35 toward the platen may be utilized in advancing a card to printing position and at the same time utilize this card advancing means for the purpose of holding the card stationary during the instant when the 40 printing operation is being accomplished.

A further object is to provide an improved card retaining magazine of simple, durable and inexpensive construction, and to provide spring actuated bearing pieces 45 to coöperate with the sliding member that advances the cards to thereby hold these parts so close together as to avoid the possibility of portions of the thin cards entering between the sliding plate and the magazine frame after the parts have become 50 worn by long use.

A further object is to provide an adjustable and detachable card stop shaped to fit the contour of the cards being used, whereby the device may be adjusted to print upon 55 any selected portion of the card.

A further object is to provide improved means for automatically removing the card after it has been printed upon, and depositing the same in a suitable receptacle. 60

Our invention consists in the construction arrangement and combination of the various parts of the device, whereby the objects contemplated are attained, as hereinafter more fully set forth, pointed out in our claims, 65 and illustrated in the accompanying drawings, in which:

Figure 1 shows a side elevation of a part of a laundry marking machine equipped with a card holding and feeding device embodying our invention. 70

Fig. 2 shows a front elevation of the card holding and feeding mechanism.

Fig. 3 shows a top or plan view of the same. 75

Fig. 4 shows a longitudinal, vertical, sectional view through the card handling mechanism.

Fig. 5 shows a vertical, sectional view on a larger scale of a part of the card holding 80 and feeding mechanism.

Fig. 6 shows a detail, sectional view of a portion of the card handling mechanism, and

Fig. 7 shows an enlarged detail, sectional 85 view illustrating the bearing devices of the magazine upon the main frame.

In the exemplification of our invention, illustrated in the drawings herewith, we have employed the reference numeral 11 to indicate generally part of the supporting frame of a laundry marking machine, which may be similar to that now manufactured by the National Marking Machine Company of Cincinnati, Ohio, under the patent to California, No. 1,059,659, issued April 22, 1913. 95

Mounted on the support 11 is a movable type carrying means 12, carrying the type 13. Mounted on the main frame of the marking machine, and preferably detachable therefrom, is a support 10. Another frame member 14 is formed on or connected 100

with the support 10. The frame members 10 and 14 support the frame members 15 of the card handling and feeding mechanism.

This type carrying means 12, when in operation, moves from the position shown in Fig. 1 to the position shown by the dotted lines in Fig. 4, and when in the latter position the type wheels coact with the platen 34 to print upon the article held on the 10 platen.

In order to utilize the movement of this type carrying means 12 for the purpose of feeding cards or tags from a magazine so that they may be printed upon by the type 15 wheels, we have provided a suitable magazine and operating mechanism therefor as follows: The frame member 15 is detachably mounted upon the support 10 of the marking machine. On top of the frame member 20 15 is the supporting base or platform 16 of the card magazine and feeding device. This base or platform has a transversely extended guide member 17 provided with the upright guide ribs 18 at its edges. Slidingly mounted 25 on the guide 17 is the magazine indicated generally by the reference numeral 19, and containing one or more separate compartments. In the present instance three are shown. The interior of each compartment 30 is shaped to fit the particular cards or tags intended to be used. The compartments of this magazine are indicated by the numeral 16. At the bottom of the magazine 19 are flanges 21 which engage the guides 18 to prevent 35 forward or rearward movement of the magazine. In order to secure the magazine in position with either one of its compartments in position to deliver cards to be printed upon, we have provided a spring 25 40 fixed at one end to the guide 18 and having its other end in engagement with a ball 24, which ball extends through an opening 23 in the guide 18 and is capable of partially entering a notch 22 in the flange 21. A suitable 45 number of these notches 22 are provided, so that when the magazine is moved laterally in its guide it will be locked and held in position with any one of the compartments 20 in position to deliver cards to 50 the printing mechanism.

In order to remove the lower card from the compartment of the magazine that is over the center of the device, the platform 16 is provided with two guides 26, and slidingly mounted in said guides is a card carrying platform 28 having at its rearward end a depression in which is a detachable plate 30 which may be changed to allow for different thicknesses of cards. Below the center 55 of the detachable plate 30 is a downwardly extended shoulder 31, which is designed when the sliding platform 28 is at its rearward limit of movement, to engage and rest upon the platen 34 of the laundry 60 marking machine, as illustrated in Fig. 5.

Adjacent to the forward edge of the detachable plate 30 is a detachable metal bar 29, the shape of which may be made to conform to the shape of the adjacent edge of the cards being printed upon. The magazine 70 itself with its three compartments is preferably cast complete of a single piece of aluminum or other metal.

It is desirable in a machine of this kind to provide means for preventing the sliding 75 platform 28 from wearing away the lower surface of the card magazine, and it is also desirable that the lower surface of the card magazine fits tightly at all times against the top of the sliding platform. For this purpose I have provided the structure illustrated in Fig. 7, and which consists of a steel plate 34^a adjustably supported by screws 34^b at one side edge of the card magazine. At the bottom of the card magazine at this 80 same edge is a hardened steel plate 34^c, which stands spaced apart from the sliding platform 28 a distance corresponding to the thickness of one card, and the steel plate 34^a projects below the plate 34^c. The central 85 ones of the partitions in the magazine have hardened steel plates 34^c and a central hardened steel plate 34^d, the latter being held downwardly by the spring 34^e. The inner faces of the plates 34^c and 34^d are shaped 90 to conform to the contour of the card being printed upon, and the plates 34^a and 34^c are designed to be engaged by the extreme end projections of the cards. By this arrangement the weight of the magazine always 100 holds the ends plates 34^a in frictional engagement with the sliding platform by the spring 34^e, so that after considerable use the parts will not be greatly worn, and the wear that takes place will be compensated for by 105 the weight of the magazine and said spring.

By the arrangement just described, it is obvious that when the card magazine is filled with cards and the sliding platform is moved rearwardly the card that rests directly upon the detachable plate 30 will be engaged by the steel plate 29 and moved rearwardly to position to be printed upon.

It is desirable in a machine of this kind to provide a means for moving these cards 115 rearwardly and then just at the instant of printing to have the cards held stationary. In order to accomplish this desirable result and at the same time operate the sliding platform directly by power obtained from 120 the moving support of the type wheels, we have devised the following mechanism: Formed on the lower central portion of the sliding platform 28 are two downwardly extending arms 45 and 46, the lower end of 125 the arm 46 being inclined downwardly and toward the marking machine at an angle of about forty-five degrees. Between these arms 45 and 46 is a shaft 44 fixed to the 130 crank arm 43, which in turn is fixed to the

rotatable shaft 40, which also has a crank arm 41 fixed to it. This crank arm 41 is connected by a rod 42 with the frame 12 of the type wheels. The said shaft 44 is provided with a flat face 48. These parts are so arranged and proportioned that when the frame 12 is in its elevated position, as shown in Fig. 1, the shaft 44 and the adjacent parts are in the position shown in Fig. 10 4. Then when the frame 12 of the type wheels is at its downward limit of movement, the shaft 44 and adjacent parts will be in the position shown in Fig. 5. That is to say, the entire sliding platform will 15 have been moved to its rearward limit, and when it reaches its rearward movement the flat face 48 will have engaged the inclined surface of the arm 45 thus holding the sliding platform in stationary position, or at 20 least preventing it from further rearward movement during the last part of the rearward movement of the shaft 44. When in the position shown in Fig. 5 these parts serve to positively prevent forward movement 25 or rebound of the sliding platform. Then when the shaft 44 moves forwardly it will move without moving the sliding platform until the shaft 44 strikes the arm 46. By this arrangement it is obvious that this 30 printing device may be operated at relatively high speed and the card to be printed on and the sliding platform which supports it will all remain stationary for the instant during which the printing is being accomplished, thus avoiding the possibility of blurring in printing from the type when 35 the cards are in contact with it.

After the card has been printed upon, we have provided means for removing it from 40 the sliding platform as follows: Mounted upon the rear guide 18 at its central portion, are two card ejecting pins 35 with their lower ends beveled or inclined downwardly and rearwardly, which ejecting pins are adjustably supported by the set screws 36. The cards rest upon the detachable plate 30, and when there is no pressure on the top of the cards a card will expand enough to project the forward edge of the card slightly 45 above the plate 29. Then when the card reaches the ejecting pins 35 these pins will engage the forward edge of the card and upon further forward movement of the sliding platform the card will be held stationary until the card platform moves forwardly from beneath the card. In order to tilt the card downwardly at one end so that it may slide downwardly into the delivery chute hereinafter described, we have provided a card striker device 37 fixed to the chute 39 in the position shown in Fig. 3. When the card drops the one end immediately strikes this horizontal wire, compelling the card to turn about this wire as a 50 hinge, preventing the card from flopping 55 around and dropping into the chute in an irregular manner, whereupon the card will drop into the chute 39 and be conducted through this chute to the card receptacle 14 where the cards may be held until it is desired to remove them. 70

At the rear of the stationary frame member 26 is a stop device for the sliding platform, consisting of a pad 47 made of leather or other suitable yielding material, and above this stop device is a card stop 51 detachably and adjustably mounted thereon by the set screws 49 in the slots 50. The card stop is shaped to conform to the edge of the card to be printed upon. 75

In practical use the device may obviously be readily, quickly and easily attached to or removed from the laundry marking machine, so that the laundry marking machine may be used for its ordinary purpose and then 80 when it is desired to use it for printing cards, tags and the like, the attachment may be applied and connected up ready for use. It is obvious that in a printing device of this kind it is essential that the movement of the sliding platform be accurately timed with relation to the movement of the printing wheels. By means of our improvement this movement is accurately timed without any possibility of getting out of 85 step with the type wheels, because it is directly connected with the movable type wheel frame and is operated thereby, thus making a very simple and effective operating means for the card printing attachment. 90 It is obvious further that our improved means for temporarily holding the card to be printed on in a stationary position at the movement of the printing impact is very 95 simple and inexpensive and efficient, for 100 even if the sliding platform moves at a high rate of speed and strikes with considerable force upon the leather sliding platform stop at the rear, there can be no rebound because the shaft 44 and the arm 45 are 105 in engagement with each other in the manner shown in Fig. 5.

In a machine of this kind, it is also desirable to have the article that is being printed upon placed upon a yielding cushion or 110 platen. In our improvement we have provided the detachable plate 30 for this purpose, and in addition to the detachable plate 30 the rear end of the sliding platform has the lug 31 so arranged that it will engage 115 and rest upon the yielding plates 34 of the printing machine during the moment of the printing impact, thus providing additional yielding support for the card being printed on. We have also so constructed and 120 designed the entire device that it is of extremely simple construction, and the parts that come in contact with the cards and that are subjected to wear, are made of hardened 125 steel plates and are so arranged that any 130

1
wear that might take place is readily compensated for.

We claim as our invention:

1. In a device of the class described, the combination with a marking machine having a movable type carrying member capable of movement to printing position, of a card magazine, a sliding member capable of removing a card from the magazine to printing position, arms spaced apart from each other and extending downwardly from said sliding member, one of said arms being provided with a beveled or inclined portion, a shaft rotatably supported, a crank arm 10 fixed to said shaft, a shaft carried by the crank arm and extended between said spaced arms, and provided with a flat portion to coact with said beveled or inclined portion when the sliding member is moved to printing position, a second crank arm on the crank shaft, and a rod connecting it with the movable type carrying frame.
2. In a device of the class described, the combination of a card magazine containing a number of compartments, a sliding member to move under the card magazine, and means for compensating for wear between the card magazine and the sliding member, said means comprising a hardened metal 25 plate at one side of the magazine to engage the sliding member, and a movable spring actuated hardened plate between the ends of the card magazine to extend downwardly with its lower end in engagement with the sliding member whereby the weight of the card magazine will hold the outer hardened plate to position and the intermediate hardened plate will be held to position by spring pressure.
3. The combination with a marking machine comprising a frame, a yielding platen carried by the frame, and type capable of movement toward and from the platen, of a card printing attachment comprising a frame designed to be detachably secured to the marking machine frame, a card receptacle in the card printing frame, and a combined card holder and card platen in the card printing frame slidably mounted for movement from position below the card receptacle for receiving a card, to position above and resting upon the yielding platen of the marking machine, whereby printing may be effected upon a card carried by the card holding platen, and the platen of the marking machine will coact therewith in providing a yielding support for the card platen when in printing position.
4. The combination with a marking machine comprising a frame, a yielding platen carried by the frame, and type capable of movement toward and from the platen, of a card printing attachment comprising a frame designed to be detachably secured to the marking machine frame, a card recep-

tacle in the card printing frame, a combined card holder and card platen in the card printing frame slidably mounted for movement from position below the card receptacle for receiving a card, to position above and resting upon the yielding platen of the marking machine, whereby printing may be effected upon a card carried by the card holding platen, and the platen of the marking machine will coact therewith in providing a yielding support for the card platen when in printing position, and means connected with the movable type of the printing machine, for effecting a sliding movement of the card platen in conformance with the movement of the type.

5. In a device of the class described, a frame having a pair of transverse guides and a pair of longitudinal guides formed therein, the frame having a row of depressions formed therein parallel with and adjacent to the longitudinal guides, a platen adapted to reciprocate in the transverse guides, a magazine comprising plural compartments adapted to reciprocate in the longitudinal guides, a laterally projecting lug fixed to the magazine having an opening therein adapted to register successively with each of said depressions in the frame when the magazine is reciprocated on the longitudinal guides, a ball loosely received in said opening and adapted to partially enter said depressions when the opening registers therewith, and means for yieldingly pressing said ball downwardly.

6. In a device of the class described, a frame, a magazine mounted thereon, a movable member adapted at the forward limit of its movement to receive a card from the magazine and at the rearward limit to present the card to a type carrying frame for printing, a vertically adjustable rod mounted on the frame above the path of the movable member and between its receiving and printing positions, said rod having its lower end beveled upwardly and forwardly.

7. In a device of the class described, a frame, a movable member adapted to reciprocate therein, a magazine mounted on the frame with the receptacle therein above the movable member when at the forward limit of its movement, a plate detachably fixed to the movable member and adapted to form a shoulder thereon which registers with the forward edge of the magazine receptacle when said movable member is in its forward position, and a second plate detachably fixed to the frame and having its forward edge adapted to abut against the rear edge of the card being printed when the movable member is at the rearward limit of its movement.

8. In a device of the class described, a frame, a magazine mounted thereon, a movable member adapted to receive a card from

the magazine when in one position and to present the card for printing when in another position, a plate detachably fixed to the movable member and forming a shoulder thereon adapted to conform to the contour of one edge of the card being printed, and a second plate detachably fixed to the frame and having one edge adapted to conform to the contour of the other edge of the card,

said second plate being so placed on the frame that the longitudinal edges of the card will abut against the correspondingly shaped edge of the plates when the movable member is in printing position.

Des Moines, Iowa, February 23, 1915.
